PAPER BOTTLE CAP

Duryea Bensel, New York, N. Y., assignor, by
mesne assignments, to Albert Borden, New
York, N. Y.

Application December 9, 1936, Serial No. 114,897

11 Claims. (Cl. 215—38)

The present invention relates to an improvement in bottle caps, preferably made of paper, and is especially adapted to form a temporary closure for milk and cream bottles, although not necessarily limited thereto.

Amongst the main objects of the present improvement is in the provision of a paper cap which is leak-proof, is arranged to embrace the bottle mouth or pouring zone thereof, thereby to keep the same sanitary and clean.

Further objects are to eliminate the so-called paper disc seal and the cost thereof, and to provide means in the cap whereby to develop an openable, extended pouring spout, which is closable, when not in use, to protect the unused contents in the bottle, and which cap may be discarded when the bottle is empty.

In bottle closing position on a bottle, the present device forms a liquid tight seal, is easily converted to a pouring device and is easily removed from the bottle, and is easily and readily applied to a bottle to seal the same.

The foregoing, and other advantages and functions will be readily ascertained as the herein description proceeds and it will be obvious that modifications may be made in the structure herein, without departing from the spirit hereof or the scope of the appended claims.

In the drawing,

Fig. 1 is a plan view of the cap as sealed;

Fig. 2 is a view similar to Fig. 1, with the cap shown in the first step of converting it into a pouring spout;

Fig. 3 is a side view of the cap converted into a pouring spout shown on a fragmented bottle neck;

Fig. 4 is a sectional view taken on the line 4—4, Fig. 1, looking in the direction of the arrows;

Fig. 5 is a reduced size layout of the bottle cap blank;

Fig. 6 is a fragmentary view, in elevation, showing a step in sealing the bottle cap;

Fig. 7 is a plan view of the cap showing the positions of the coating parts thereof when being closed, for sealing; and

Fig. 8 is an enlarged, sectional, fragmentary view, taken on the line 8—8, Fig. 5 looking in the direction of the arrows.

The single blank, Fig. 5, shows a complete, cap forming structure and comprises four main sections 5, 6, 7 and 8 defined from each other by score lines d, e and h, with a glue lap 9 on section 6 defined therefrom by score line a.

Each main section 5, 6, 7 and 8 has a depend-

ing, adjacent skirt section 2, 4, 1 and 3, respectively, all of the skirt sections being defined from their respective main sections by a common score line l, and each of the skirt sections is slitted from one another by cut scores i, j and k, the slits ending at the score line l.

The independent skirt sections, further, are corrugated transversely of the blank as at 16, 16, Figs. 5 and 8, the corrugations, or crimping, ending at the score line l.

The main section 6 has two substantially triangular sub-sections 10 and 11, these being defined from section 6 by diagonal score lines b and c, respectively, which commence at the lower opposite corners of section 6, at the score line l, and merge into an apex at the mid-portion of section 6 at its outer edge. Section 5 is likewise provided with triangular sub-sections 12 and 13 defined by diagonal score lines f and g which run the same as described for lines b and c.

Triangular sub-sections 10 and 13 have their exposed edges extending beyond the main edge 17 of the blank, these extensions being in the form of curved tongues T—T, and act as tuck and lock flaps, as will be later described in detail.

The main section 8 is provided with an extension 14, these sections 8 and 14 forming a top covering flap, when in bottle sealing position, and also form, in part, a portion of the pouring spout or extension as will be later described. The sections 8—14 has a short line of weakened resistance 15, Fig. 5, which enters at the mid portions of said sections and ends at the center of the combined sections. The purpose of the weakened line 15 will be later described.

The main sections 8—14 is also provided with triangular sections 27 and 28, these being defined from said sections by angularly disposed score lines n and o, said score lines being at an angle to the weakened line of resistance 15, whereby when said line 15 is ruptured, flaps 27 and 28 may then be bent upwardly and rearwardly on said scores n and o, for purposes to be later described.

To erect the blank into a bottle cap sealing structure, the glue lap 9 is touched with glue, as indicated by the stippling thereon, and the blank is then folded on the score lines a, d, e and h and the lap 9 is attached to the inside face of panel 7 at 18, Fig. 7, thus forming, in this first step, a rectangular tube.

The one piece tube thus formed comprises a cap forming or sealing portion, the component parts of which are connected to one another, and a crimped bottle neck embracing or skirt portion,

the coacting elements of which are connected to the cap or sealing portion but which are slitted from one another.

After the glue lap attachment has been made 5 as above described, the cap or sealing cover is bent down by pressing inwardly the two triangular sub-sections 5 and 6, which when the tube is erected, lie opposed to one another while the sections 8-14 and 7 are opposite one another, as 10 shown in Fig. 7.

The bending inwardly of sub-sections 5 and 6, due to their scored connections to the next adjacent subsections 12 and 13 and sub-sections 10 and 11, respectively, draw these sections inwardly also, and the sub-sections 10-11 and 12-13 due to their scored connections with the main sections 7 and 8-14 also draw these latter inwardly and downwardly, in part indicated in Figs. 6 and 7. Thus, when finally closed down flat, the 15 triangular sub-sections 5 and 6 lie lowermost, with the tabs T tucked in between sub-flaps 11-12 and main flap 8, triangular sub-sections 10-11 and 12-13 lie upon sub-sections 5 and 6 in the next plane, main section 7 lies upon sub-sections 10 and 13 in the next higher plane and 20 cover or cap section 8-14 overlies the entire folded structure in the highest or top plane. The section 14 is glued to section 7 on final closure, and this locks the folded structure in close, compact assembly.

After the glued cap folded assembly has been set, the cap is embossed in a die to form a circular indent therein as shown at 20 in Figs. 1 to 4 inclusive. This indent is of such dimensional proportions as will effectively contact with the inner edge of the mouth of the bottle 21 as at 22 Fig. 4, when in operative sealing position. This embossing operation, due to the pressure forces used, further compacts the over-folded cap forming parts into a substantially liquid tight assembly.

When the cap has thus been folded and embossed, it may be coated with a liquid proofing coating thereby to render the cap leak and moisture proof and, seal up all crevices between the 45 folded sections.

The cap is then ready to be affixed to a bottle, which is done by seating it firmly upon the bottle mouth, and gathering in the corrugated skirt forming portions about the cylindrical neck and bead portions 21 and 24, Figs. 3 and 4, whereby 50 the four skirt members 1, 2, 3 and 4 are caused to overlap on their corners as indicated at 25, Fig. 3, and by reason of the crimping 16, the skirt members are easily conformable to the contour of the bottle neck below the bead 24, as at 26, Fig. 4, after which a ductile metal ring, not shown, but which is current practice, is crimped upon the skirt at a point 26, below the bottle mouth bead, Figs. 3 and 4, thus to bind the cap 60 to the bottle.

The gathering of the skirt as it depends from the rectangular cap forming portion, to embrace the cylindrical bottle neck, does not affect the contour of the rectangular cap pouring portion, as is illustrated in Figs. 1 and 2, as the crimping of the skirt elements 1 and 4 inclusive breaks down the fibres of that portion of the cap and renders it pliable and easily conformable to the exterior portions of the bottle neck, without undue strain upon the rectangular portions of the seal.

To open the seal for pouring purposes, the seal is left affixed to the bottle in its operative position, and the weakened line of resistance 15 is

ruptured, the diagonal sub-sections 21 and 28 are then bent upwardly as in Fig. 2, and backwardly on their score lines n and o, bending up, simultaneously the under triangular sub-sections 12 and 13, and triangular section 5, being then exposed, is pulled out to the position shown in Fig. 3 and as thus developed, the adjacent connected parts and sections 5, 12, 13, 21 and 28 are reversed outwardly, on their appurtenant angularly disposed score lines to form a spout, and conversely are reset back into original sealing position to close the cap.

The spout may be opened and closed as often as is required to empty the bottle, and then removed to clean the bottle for reuse, and for receiving thereon a new sealing cap.

From the foregoing it will be noted that the pouring cap, as applied sealed to the bottle is substantially flat with no extrusions above the top, is easily iced on top by reason of the indent 20, and forms a good firm grip for manually handling of the bottles.

What I claim is:

1. The combination with a bottle having a beaded mouth portion, of a paper sealing cap, 25 said cap comprising a bottle mouth sealing portion and a skirted bottle neck engaging portion depending from said sealing portion, said sealing portion comprising a plurality of infolded, connected and scored overlapping plies of material, 30 some of said plies having interlocks to engage between other plies, others of said plies being scored to form a pull-out pouring spout, the outermost ply of the sealing means having a rupturable line of weakness therein above the spout 35 forming elements whereby, after rupturing said line, said spout forming elements may be drawn cut to form a spout.

2. A closure for a bottle having a cylindrical neck and a mouth bead, comprising a cap of 40 stiff paper including four laterally joined sections having four crimped elements extending therefrom and forming a skirt and seal, the lower parts of said elements being engageable against the cylindrical neck below the bead; said sections being folded inwardly and providing a rectangular sealing top, said top having its transverse minor diameters substantially equal to the diameter of the bead at its top; said sections including under a half of one of said minor 45 diameters a folded member, a top member over the first member and having a weakened line coinciding with said half, whereby a finger of a user may be rested on said bead to press up the outer member and tear said line, so that the under member may then be pulled out to form a 50 pouring spout.

3. The combination with a beaded mouth bottle of a paper sealing cap comprising a rectangular mouth sealing portion and a relatively flexible skirt portion joined thereto, said skirt portion being conformed to the contour of the bottle mouth at and below the said bead, and means for holding said cap and skirt in operative position on said bottle mouth, said rectangular sealing portion comprising a plurality of scored portions, which are overfolded upon one another to form a plural ply sealing portion, said overfolded portions being embossed with a central indent to compact the plural plies and a rupturable line 65 of weakness on the outermost ply of the sealing portion.

4. A paper sealing cap for a bottle having a beaded mouth, said cap comprising a stiff top-sealing-wall bounded by score lines; and a flexi- 70

ble skirt portion joined to the top wall at said score lines and conformed to the bottle neck below the bead; said skirt portion having slits extending downwardly from the top wall and dividing the skirt portion into sections adapted to be overlapped when the skirt is conformed to the neck; said sections being crimped to form the non-overlapping corrugations extending downwardly from the wall to render the skirt portion 10 freely flexible in all directions to conform to the bottle neck and to each other at the overlap.

5. A paper sealing cap for a bottle having a neck having a beaded mouth, said cap comprising a square top sealing wall bounded by straight score lines and comprising superposed plies; and a flexible skirt portion joined to the top wall at said score lines and conformed to the bottle neck below the bead; said skirt portion having slits extending downwardly from the top wall 15 and dividing the skirt portion into sections adapted to be overlapped when the skirt is conformed to the neck; said sections being crimped to form fine corrugations extending downwardly from the wall to render the sections freely flexible in all directions to conform to the bottle 20 neck and to each other at the overlap, all parts of each section being of a single thickness.

6. A paper sealing cap for a bottle having a beaded mouth, said cap comprising a top wall 25 comprising superposed plies; and a skirt portion joined to the top wall and adapted to engage the bottle neck below the bead; the outer most ply being provided with a rupturable line; another of the plies being folded to form a pull-out pouring spout beneath said line and adapted to be extended to pouring position when said line is ruptured.

7. A paper sealing cap for a bottle having a beaded mouth, said cap comprising a rectangular top sealing wall comprising superposed plies and bounded by score lines; and a flexible skirt portion joined to the top wall at said score lines and adapted to be conformed to the bottle neck below the bead; the outermost of said plies being joined to the skirt at one of said score lines and provided with a rupturable line; another of the plies being joined to the skirt at another of said score lines and being folded to form a pull-out pouring spout beneath said rupturable line and adapted to be extended to pouring position when said line is ruptured.

8. In combination, a top wall comprising superposed plies and bounded by score lines; side

portions joined to the top wall at said score lines; an outer ply being joined to a side portion at one of said score lines and provided with a rupturable line; another of the plies being joined to another of the side portions at another of said 5 score lines and being folded to form a pull-out pouring spout having adjacent edges longitudinal to and beneath said rupturable line, said spout being adapted to be extended to pouring position when said line is ruptured.

9. In a combination as in claim 8, one of said adjacent edges being formed with a tongue adapted to be projected at said weakened line when ruptured, whereby said spout may be drawn out.

10. A paper sealing cap for a bottle having a beaded mouth, said cap comprising a rectangular top sealing wall comprising superposed plies and bounded by score lines; and a flexible skirt portion joined to the top wall at said score lines and adapted to be conformed to the bottle neck below the bead; the outermost ply being joined to the skirt at one of said score lines and provided with a rupturable line; another of the plies being joined to the skirt at another of said score lines 20 and being folded to form a pull-out pouring spout having adjacent edges longitudinal to and beneath said rupturable line, said spout being adapted to be extended to pouring position when said line is ruptured; one of said adjacent edges 25 being formed with a tongue adapted to be projected at said weakened line when ruptured, whereby said spout may be drawn out.

11. A paper sealing cap for a bottle having a beaded mouth, said cap comprising a top sealing 30 wall comprising superposed plies; and a flexible skirt portion joined to the top wall and adapted to conform to the bottle neck below the bead; the outermost ply being provided with a rupturable line; an inner ply beneath said line being 35 folded to form a pull-out pouring spout held in place by said outer ply and adapted to be extended to pouring position when said line is ruptured; said skirt portion having slits extending downwardly from the top wall and dividing the 40 skirt portion into sections joining respective plies and adapted to be overlapped when the skirt is conformed to the neck; said sections being crimped to form fine corrugations extending 45 downwardly from the top wall to render the sections 50 separately flexible to conform to the bottle neck and to each other at the overlap.

DURYEA BENSEL.
